MULTIPLE-BEAM ELECTRON GUN

Robert E. Benway, Lancaster, Pa., assignor to Radio Corporation of America, a corporation of Delaware

Application April 30, 1953, Serial No. 352,095

11 Claims. (Cl. 313—70)

This invention is directed to electron discharge devices of the cathode ray tube type and more specifically to cathode ray tubes used as viewing tubes for color television.

One type of cathode ray viewing tube for color television, disclosed in the copending application of Hannah C. Moodey, Serial Number 295,225, filed June 24, 1952, utilizes three electron guns for forming three parallel electron beams arranged symmetrically about the tube axis and directed at a target electrode within the tube envelope. A combined converging and focusing lens, formed by potential differences between three electrodes, is used to converge the three electron beams to a common point on the target.

The target electrode consists principally of a masking electrode formed of a thin metal sheet having a large number of small apertures formed therethrough. The apertured masking electrode is mounted substantially normal to the tube axis and in the paths of the electron beams. Conventional means are used to scan the three beams simultaneously over the apertured mask electrode in a rectangular raster. A glass target support plate is mounted close and parallel to the side of the masking electrode opposite to the electron guns.

There is formed on the glass support plate groups of phosphor dots with each group consisting of three dots spaced 120° from a common point which in turn is aligned with one of the apertures through the masking electrode so that there is one group of phosphor dots aligned with each aperture of the masking electrode. The three phosphor dots of each group are formed respectively of phosphors luminescing in different colors as red, green, and blue.

Since the three parallel beams of the color tube are converged to a common point on the masking electrode, the electrons of each beam strike the masking electrode from substantially three different directions. As the beams are scanned over the masking electrode surface, the electrons from the three beams will pass through the apertures of the masking electrode along paths which are respectively extensions of the directions from which the beams strike the masking electrode and will strike separate phosphor dots of each group. This arrangement results in the electrons then of each beam striking phosphor dots which luminesce with one color.

A tube of the type described above can be utilized with various types of color systems in which the color signals are either formed and transmitted simultaneously or in a sequential order and in which each signal may comprise an elemental signal or a frame signal. The signals are applied each independently to the three guns of the viewing tube so that the three electron beams are independently modulated to provide the color response at the correct time interval.

Tubes of the type described above do not have optimum picture brightness because the masking electrode at the target inherently collects a large percentage of each beam. It is desirable in tubes of this type to increase the screen

2

efficiency, which is the percentage of each electron beam which strikes the phosphor spots of the target. An obvious way to increase screen efficiency would be to open the holes in the masking aperture to permit the passage of a greater proportion of each electron beam. However, the size of the apertures in the masking electrode is obviously limited to prevent the overlapping of the beams upon striking the phosphor dots whereby color dilution of the picture would result. It is also desirable in tubes of this type, for circuit reasons, to collect as little current as feasible in the gun.

It is, therefore, an object of this invention to provide a color picture tube of increased picture brightness.

It is another object of this invention to provide a color picture tube of improved gun efficiency.

It is also an object of this invention to increase the screen efficiency of a color picture tube having a beam masking electrode at the target.

The invention is specifically related to a color picture or viewing tube having a masking electrode at the target whereby electrons approaching the target from one of several directions will strike phosphor portions of the target luminescing with a single color of light. To improve the picture brightness of tubes of this type, the electron beams within the deflecting fields of the scanning yoke are made with a minimum cross section limited by the desired resolution of the picture of the tube. By decreasing the beam diameter in the deflection plane, it is possible to enlarge the apertures of the masking electrode at the target and thus to increase the picture brightness or screen efficiency of the tube. This result is accomplished by providing a substantial prefocusing lens in the path of each electron beam. The prefocusing lens also increases the gun efficiency for its respective beam whereby certain circuit problems are alleviated.

Figure 1 is a sectional view of portions of a color picture tube, in accordance with the invention.

Figure 1A is an enlarged sectional view of a portion of the gun structure of the tube of Figure 1.

Figure 2 is a sectional view along line 2—2 of Figure 1.

Figures 3, 4 and 4A are schematic representations of portions of the picture tube of Figure 1.

Figures 5 and 6 are diagrammatic showings of the beam paths in the tube of Figure 1, and in accordance with the invention.

Figures 1 and 1A show a color television picture tube consisting of an evacuated envelope 10 having an enlarged bulb or shell portion 12 fixed to a tubular neck portion 14. The tubular neck 14 and the bulb portion 12 are axially aligned along a common axis 16. Mounted at one end of the neck portion is an electron gun means 18 for providing a plurality of electron beams along paths which are symmetrically spaced from the axis 16. Mounted substantially normal to the axis 16 of the tube 10 and within the opposite end of the bulb portion 12 is a target electrode assembly 20 consisting of a thin metallic sheet 22 tightly stretched in a spaced parallel relationship over a glass support sheet 24. Details of the target construction and mounting are not given here but may be of the type disclosed, for example, as U. S. Patent 2,611,100 of R. D. Faulkner et al.

The electron gun 18 consists of a plurality of electron sources consisting of cathode electrodes 26, each of which are formed of short tubular members mounted in a parallel relationship in a ceramic insulating spacer 28 which is in turn fixed within the short tubular control electrode 30 coaxially mounted within the neck portion 14. The cathode electrodes 26 are closed at the end facing the target 20 and are coated with thermionic emitting material (not shown) for providing sources of electrons.

The control electrode 30 is closed at the end facing the target 20 by a plate member 32 having a plurality of

apertures therethrough, with one aperture aligned with each coated end of the cathode electrodes 26. Closely spaced along the axis 16 from the grid plate 32 is a first accelerating electrode plate 34 mounted in a parallel plane to that of plate 32. Accelerating plate 34 is also apertured, with one aperture aligned with each of the apertures in plate 32.

Spaced along the axis 16 is a second accelerating electrode 38 consisting of a tubular member closed at both ends by apertured plates 40 and 42, respectively. Again, each aperture in plates 40 and 42 is aligned with a corresponding aperture in the other plate and with an aligned pair of apertures in plates 32 and 34 to provide a straight line path for the passage of electrons from the respective cathode electrodes 26 through the accelerating electrode 38.

Mounted within the tubular accelerating electrode 38 is a beam masking diaphragm or plate member 44, also having a plurality of apertures with one aperture aligned with each straight line paths from cathodes 26 through the tubular electrode 38. Spaced along the axis 16 and mounted coaxially thereto is a third accelerating electrode 46 consisting of a short tubular member enclosing the straight line paths from the cathodes 26 to the screen 20; a fourth accelerating electrode is formed as a conductive coating 48 on the inner surface of the tubular envelope portion 14 and also encloses all of the straight line paths from the several cathode electrodes 26 to the screen 20.

The operation of the electron gun 18 is that in which appropriate voltages are applied to the several electrodes as indicated in Figure 1. These voltage values are in no way limiting but represent typical voltages which have been used to operate tubes of this type. Within each cathode electrode 26 is mounted a heater filament, which, during tube operation, raises the temperature of the cathode emissive material to a thermionic level. The electrons emitted from each cathode pass through the aligned apertures in plates 32 and 34. The configuration of the electrostatic field formed between plates 32 and 34, at operating potentials, causes the electrons from each cathode to form a beam having a minimum cross sectional area or "crossover point" 33 adjacent plate 34 and as schematically shown in Figure 1. From each crossover point 33 the electrons pass respectively into the tubular electrode 38 as diverging beams. The fringe portions of each beam are masked off or collected by the corresponding apertures of plate 44. The apertures in plate 42 are sufficiently large that the central portions of each beam, passing through the respective aperture of plate 44, do not strike the edges of these apertures in plate 42.

Due to the differences of potential between electrodes 38 and 46 there is formed an electron lens field 50 therebetween and as schematically shown in Figure 1. One portion of the lens field 50 extends through the apertures in accelerating electrode plate 42 to form separate fields 52, with one field 52 in the path of each electron beam. The fields 52 have a curvature of a degree that changes the electron beams from diverging beams to converging beams. The converging action of fields 52 focuses each beam to a small spot on the masking electrode 22 of target 20. Fields 52 constitute the main or principal focusing field for each electron beam, respectively.

Between the third accelerating electrode 46 and the accelerating electrode coating 48, there is also established an electron lens field 54 having somewhat the configuration schematically shown in Figure 1. All of the beams pass through the common field 54 and the nature of the field is to provide convergence of each beam toward the field axis which is common with axis 16 of the tube. Field 54 is adjusted to bring the several beams to a common point of convergence on the axis 16 and at the target masking screen 22. The common converging field 54 also adds somewhat to the focusing of the

electrons in each beam to a minimum spot on the masking electrode 22 of the target. The operation of the gun 18, as described above is similar to that described in the above cited copending application of Hannah C. Moodey.

On the surface of the glass support plate 24 of target 20, there is formed a large number of phosphor dots 56 and as shown more specifically in the enlarged sketches of Figures 3 and 4. The phosphor dots 56 are arranged in groups of three, with the dots in each group spaced 10 120° about a common center point 55. Each dot in every group is formed of a different fluorescing phosphor material and, as indicated in Figures 3 and 4, the phosphor materials will luminesce with red, green, or blue light 15 respectively when struck by high energy electrons. Figure 3 shows specifically one group of phosphor dots 56 and arranged as described above. The center 55 of the group is aligned with one aperture 58 of the masking electrode 22 and the arrangement is such that each of the apertures 58 of electrode 22 has a corresponding group of 20 three differently fluorescing phosphor dots aligned therewith and in a similar manner.

As shown in Figure 3, the screen structure is such that the alignment of each separate phosphor dot with its respective aperture 58 is along a directional line X, 25 Y, or Z, which forms a small angle with the line determined by the center of each aperture 58 and the center 55 of the respective group of phosphor dots. This provides a structure such that electrons passing through 30 the aperture 58 of Figure 3 along each one of the directional lines X, Y, or Z will strike only one of the phosphor dots. The arrangement is utilized in forming the target electrode as shown in more detail in Figure 4 in which three electron beams, corresponding to those shown in Figure 1, upon converging to a common point 35 on the masking screen 22 will approach the screen each from a different direction X, Y, or Z, which makes a small angle of incidence to the normal of the masking electrode 22. The electrons of each beam striking the common point or spot of convergence on masking electrode 22 will pass through whatever apertures 58 are 40 covered by the beam spot. Furthermore, the electrons passing through these apertures 58 will continue in the same direction X, Y, or Z of their approach to screen 22 and will strike the specific phosphor spot aligned with each aperture 58 in that direction. Thus, from 45 Figure 4 it can be seen that all of the electrons from one beam passing through electrode 22 will only strike those phosphor spots which fluoresce with the same color and the screen 22 will mask the electrons of each beam from all of the other phosphor spots fluorescing with the other colors.

Means are provided for scanning the three beams of Figures 1, 3, and 4 over the surface of the target 20. The deflecting means are shown schematically as a yoke structure 60 mounted on the tubular envelope portion 14. The yoke 60 is of a conventional design and operation and is constituted principally of two pairs of coils, with the coils of each pair connected in series with each other to a source of saw tooth currents for providing line and frame scansion of the electron beams over the surface of target 20. The operation of the tube described is also disclosed in greater detail in the above cited copending application of Hannah C. Moodey.

In tubes of the type described, it is desirable to obtain a maximum screen brightness. However, since the masking aperture plate 22 at the target absorbs a large percentage of the beam current, the brightness of the picture obtained is not a maximum. Also, as set forth in the article by H. B. Law, page 466 of the RCA Review, Part II, September 1951, the screen efficiency can be expressed as the product of a constant K and the quantity

$$75 \quad \left(\sqrt{3} - \frac{M}{s} \right)^2$$

where M is the beam diameter in the deflection plane and S is the beam-to-axis spacing in the deflection plane.

As shown in Figure 1 when each beam is deflected by the fields of yoke 60 the direction of the beams is changed from the axis of the tube to approach the target 22 from a different direction. Each beam may be considered as originating from a deflection plane P , which is substantially at the center of the coils of the yoke 60. This plane can be determined, as schematically shown in Figure 1, by projecting each beam path backwards onto its respective undeflected beam path. The points where the projected paths of the several beams meet their undeflected paths respectively determine this plane of deflection.

From the above relationship, expressed for the screen efficiency of a tube of the type described, it can be seen that the reduction of each beam diameter, M , within the deflection plane increases the screen efficiency. This is due to the fact that, an electron beam of smaller diameter in the deflection plane, will cover less area of each phosphor spot 56. This effect is shown more specifically in Figure 4A where M_1 represents a beam of a given diameter. Fringe electrons from the edge of the beam M_1 striking the edge of an aperture 58 will strike the edge of a corresponding phosphor dot 56. The paths of these fringe electrons are indicated by the solid lines drawn through aperture 58 to the edge of the spot 56. The solid lines thus determine the spread of the beam M_1 in passing through aperture 58. Aperture 58, then, must be sufficiently small to prevent the fringe electrons from spreading beyond the spot 56 to strike additional neighboring phosphor spots and thus cause color dilution in the picture. However, if the beam diameter is made smaller such as that indicated by M_2 , for example, the spread of the beam, is smaller as indicated by the dotted lines representing the beam paths of the fringe electrons. Beam M_2 strikes a smaller surface area of the corresponding spot 56. Because of this, then, the aperture 58 may be opened until the fringe electrons of the beam M_2 will strike the edge of spot 56. By opening the aperture 58, more of the beam passes through the aperture to strike the phosphor spot 56 and thus produce a brighter fluorescence from spot 56. This procedure increases the screen efficiency as described.

In accordance with the invention, then, there is established between the crossover points 33 of each beam and the respective focusing lens 52, an additional pre-focusing lens 62, with one of each lens 62 in the path of each of the electron beams. Focusing fields 62 are formed by mounting on the face of plate 34, facing the target, a plurality of apertured cup-like structures 63, forming short tubular extensions of the apertures in plate 34. Cups 63 are mounted on plate 34 with the open end of each cup facing the target electrode 20, and with the aperture in the bottom of each cup 63 coaxially positioned about a corresponding aperture in plate 34. The pre-focusing lenses 62 are formed by establishing an appropriate difference of potential between electrodes 34 and 38. The cup electrodes 63 form each lens field 62 into one having a sharp curvature dipping into each cup 36 respectively. This is shown schematically in Figure 1.

The effect of the pre-focusing lens field 62 is shown schematically in Figures 5 and 6. As shown in Figure 5 the electron emission from cathode 26 passes in substantially straight lines from the cathode emitting surface through the first crossover point 33, through the masking aperture 44 to the main focusing lens 52, and then in substantially straight converging paths through the deflection plane P to the target 20. The lens system of this type is one in which the first crossover region 33 of the beam is imaged on the target 20. Since the first crossover point 33 is that portion of each beam having a minimum cross sectional area, the size of the beam spot on the target 20 is

determined by the magnification of the lens system and, as is well-known in the art, is proportional to the ratio of the image distance to the object distance. As shown in Figure 5, the object distance is that distance from the first crossover point 33 to the main focusing lens 52 and the image distance is substantially that distance from the main focusing lens 52 to the screen 20.

Figure 6 illustrates the effect of placing a pre-focusing lens 62 between the first crossover point 33 and the main focusing lens 52. The lens 62 decreases the divergence of the electron beam from the first crossover point 33. Furthermore, the beam width or beam diameter is made smaller by lens 62 between the pre-focusing lens and screen 20 and particularly so in the deflection plane. This enables the use of larger apertures 58 in the target masking electrode 22 and in this manner increases the screen efficiency and the brightness of the picture of the tube as pointed out above.

However, from Figure 6 it can also be seen that the effect of using the additional pre-focusing lens 62 is the same as that of moving the main focusing lens 52 toward the first crossover point 33. Actually, the two lenses have the same optical effect as a single equivalent lens identified by the dotted line 66 positioned between the plane of the main focusing lens 52 and the location of the pre-focusing lens 62. The position of this resultant single lens can be determined by projecting the electron paths from the first crossover point along their diverging directions and by projecting backward the electron paths from their converging directions. The intersections of these projections determine the plane 66 of the resultant single lens. The object distance then of the new lens system is substantially the distance from the first crossover point 33 to the plane 66 of the resultant single lens, and the image distance is that from this plane 66 to the screen 20. The magnification is again proportional to the ratio of the image distance to the object distance which is larger than in the previous lens system of Figure 5, due to the increase in length of the image distance and the decrease in length of the object distance. The increased magnification of the lens system results in the beam spot at the target 20 becoming larger. The magnification depends on the strength of the pre-focusing lens field 62. It is therefore necessary to determine an optimum relationship between the picture resolution desired and the screen efficiency or picture brightness. In tubes of the type described, the resolution of the picture has been chosen as that of 700 lines and the pre-focusing lens 62 is adjusted to provide this resolution with a resultant decrease of beam diameter in the deflection plane. The apertures 58 are constructed then with increased openings to accommodate the change in beam diameter and to provide a brighter picture than previously obtained.

The size chosen for the cup electrodes 63 is determined by the shape of the field which they are to produce. The diameter of the cups can not be too small as the electron beam would then tend to pass through the edges of the fields 62 and would introduce beam distortions. Furthermore, the diameter can not be too large as they would not provide sufficient curvature of the field to give the desired focusing effect. Furthermore, the diameter of the cups is limited by the spacing of the apertures in plate 34. In a tube of the type described, the apertures in plate 34 were spaced at approximately 6.2 mm. This permitted the use of cups 63 having a depth of 3 mm. and a diameter of approximately 6 mm. Also the cup depth determines the strength of the pre-focusing field 63: the field becomes stronger as the depth of the cup is increased since the field curvature is increased.

Figure 6 also discloses an additional advantage of using pre-focusing fields in accordance with the invention. The shaded areas in Figures 5 and 6 schematically indicate the amount of the electron beam which is lost by being collected by the aperture of the masking electrode 44. For the same beam emission and as shown in Figure 6, the

use of the prefocusing lens 62, by introducing convergence in the beam, permits more of the beam to pass through the aperture of the plate 44. This results in higher gun efficiency, which is desirable for circuit reasons.

In the manner described above and in accordance with the invention the use of the prefocusing lenses 62 increases both the screen efficiency and the beam density which results in each case in increasing the picture brightness of the tube. This then permits using the maximum efficiency of the color screen unit and yet still retaining a high degree of picture resolution. As described, the invention is that in which a proper balance is obtained between the efficiency of the screen unit, the efficiency of the gun, and the picture resolution.

While certain specific embodiments have been illustrated and described, it will be understood that various changes and modifications may be made therein without departing from the spirit and scope of the invention.

What is claimed is:

1. An electron discharge device comprising, electron gun means for providing a plurality of beams along respective paths in a common general direction, a target electrode mounted transversely to said beam paths, said gun means including electrode structure for providing a common electrostatic converging lens in the paths of the electron beams, electrode means for providing a plurality of principal focusing lenses, one of said focusing lenses in the path of each electron beam, and electrode means for forming a plurality of prefocusing lenses one in the path of each beam.

2. An electron discharge device comprising electron gun means for providing a plurality of electron beams along respective paths spaced from a common axis, a target electrode spaced from said electron gun means and mounted transversely to said beam paths and said common axis, said electron gun means including cathode means and a first and a second electrode spaced along said axis between said cathode means and said target for providing a plurality of converging lenses one in the path of each beam, a third electrode spaced along said axis between said second electrode and said target for forming a plurality of principal lenses one in the path of each of said beams.

3. An electron discharge device comprising electron gun means for providing a plurality of electron beams along respective paths spaced from a common axis, a target electrode spaced from said electron gun means and mounted transversely to said beam paths and said common axis, said electron gun means including cathode means and a first and a second electrode spaced along said axis between said cathode means and said target for providing a plurality of converging lenses one in the path of each beam, a third electrode spaced along said axis between said second electrode and said target for forming a plurality of principal lenses one in the path of each of said beams, said first electrode including a plurality of apertured cup electrodes, and means mounting one cup electrode coaxially on each beam path with the open end of each cup electrode adjacent said second electrode.

4. An electron discharge device comprising electron gun means for providing a plurality of electron beams along respective paths spaced from a common axis, a target electrode spaced from said electron gun means and mounted transversely to said beam paths and said common axis, said electron gun means including cathode means and a first and a second electrode spaced along said axis between said cathode means and said target for providing a plurality of converging lenses one in the path of each beam, a third electrode spaced along said axis between said second electrode and said target for forming a plurality of principal lenses one in the path of each of said beams, said first electrode including a plurality of apertured cup electrodes, and means mounting one cup electrode coaxially on each beam path with the open end of each cup electrode adjacent said second electrode.

trode, said second gun electrode comprising a tubular member mounted coaxially with said common axis and a plate member closing each end of said tubular member, said plate members each having a plurality of apertures therethrough with one aperture in each plate aligned with each beam path for the passage of the respective beam.

5. An electron discharge device comprising electron gun means for providing a plurality of electron beams along respective paths spaced from a common axis, a target electrode spaced from said electron gun means and mounted transversely to said beam paths and said common axis, said electron gun means including cathode means and a first and a second electrode spaced along said axis between said cathode means and said target for providing a plurality of converging lenses one in the path of each beam, a third electrode spaced along said axis between said second electrode and said target for forming a plurality of principal lenses one in the path of each of said beams, said first electrode including a plurality of apertured cup electrodes and means mounting one cup electrode coaxially on each beam path with the open end of each cup electrode adjacent said second electrode, said second gun electrode comprising a tubular member mounted coaxially with said common axis and a plate member closing each end of said tubular member, said plate members each having a plurality of apertures therethrough with one aperture in each plate aligned with each beam path for the passage of the respective beam, and a masking plate mounted within and intermediate the ends of said tubular member, said masking plate having a plurality of apertures therethrough with one aperture aligned with the center of each beam path for masking the outer portions of each beam respectively.

6. An electron discharge device comprising electron gun means for providing a plurality of electron beams along respective paths spaced from a common axis, a target electrode spaced from said electron gun means and mounted transversely to said beam paths and said common axis, said electron gun means including cathode means and a first and a second electrode spaced along said axis between said cathode means and said target for providing a plurality of converging lenses one in the path of each beam, a third electrode spaced along said axis between said second electrode and said target for forming a plurality of principal lenses one in the path of each of said beams, and a common deflecting means between said gun means and said target electrode for scanning said beams over said target.

7. An electron discharge device comprising electron gun means for providing a plurality of electron beams along respective paths spaced from a common axis, a target electrode spaced from said electron gun means and mounted transversely to said beam paths and said common axis, said electron gun means including cathode means and a first and a second electrode spaced along said axis between said cathode means and said target for providing a plurality of converging lenses one in the path of each beam, a third electrode spaced along said axis between said second electrode and said target for forming a plurality of principal lenses one in the path of each of said beams, said first electrode including a plurality of apertured cup electrodes and means mounting one cup electrode coaxially on each beam path with the open end of each cup electrode adjacent said second electrode, said second gun electrode comprising a tubular member mounted coaxially with said common axis and a plate member closing each end of said tubular member, said plate members each having a plurality of apertures therethrough with one aperture in each plate aligned with each beam path for the passage of the respective beam, and a common deflecting means between said gun means and said target electrode for scanning said beams over said target.

8. An electron discharge device comprising, electron gun means for providing a plurality of electron beams along respective paths spaced from a common axis, a

target electrode spaced from said electron gun means and mounted transversely to said beam paths and said common axis, said electron gun means including cathode means and a first and a second electrode spaced along said axis between said cathode means and said target for providing a plurality of converging lenses one in the path of each beam, a third electrode spaced along said axis between said second electrode and said target for forming a plurality of principal focusing lenses one in the path of each of said beams, said first electrode including a plurality of tubular electrodes and an apertured plate, said plate having an aperture in the path of each of said beams, said tubular members mounted on said plate with one tubular member over each aperture and an open end adjacent said second electrode.

9. An electron discharge device comprising, electron gun means for providing a plurality of electron beams along respective paths spaced from a common axis, a target electrode spaced from said electron gun means and mounted transversely to said beam paths and said common axis, said electron gun means including cathode means and a first and a second electrode spaced along said axis between said cathode means and said target for providing a plurality of converging lenses one in the path of each beam, a third electrode spaced along said axis between said second electrode and said target for forming a plurality of principal focusing lenses one in the path of each of said beams, said first electrode including a plurality of tubular electrodes and a plate having an aperture therethrough aligned with each beam path, and means mounting one of said tubular electrodes coaxially on each beam path with one end enclosing an aperture through said plate and with the other end of each of said tubular electrodes adjacent said second electrode.

10. An electron discharge device comprising, electron gun means for providing a plurality of electron beams along respective paths spaced from a common axis, a target electrode spaced from said electron gun means and mounted transversely to said beam paths and said common axis, said electron gun means including cathode means and a first and a second electrode spaced along said axis between said cathode means and said target for providing a plurality of converging lenses one in the path of each beam, a third electrode spaced along said axis between said second electrode and said target for forming a plurality of principal focusing lenses one in the path of each of said beams, said first electrode including a plurality of tubular members and an apertured plate, said plate having an aperture in the path of each of said beams, said tubular members mounted on said plate with 50

one tubular member over each aperture and an open end of each of said tubular members adjacent said second electrode, said target electrode including a support plate having a plurality of groups of phosphor dots with one phosphor dot of each group having a different color of luminescence when bombarded with electrons, and a masking electrode closely spaced from said support plate between said support plate and said electron gun means for masking all except one of the phosphor dots of each group from the electron beam of each gun.

11. A cathode ray tube comprising, electron gun means for providing a plurality of electron beams along respective paths spaced from a common axis, a target electrode spaced from said electron gun means and mounted transversely to said beam paths and said common axis, said electron gun means including cathode means and a first and a second electrode spaced along said axis between said cathode means and said target for providing a plurality of converging lenses one in the path of each beam, a third electrode spaced along said axis between said second electrode and said target for forming a plurality of principal focusing lenses one in the path of each of said beams, said first electrode including a plurality of tubular members and a plate having an aperture therethrough aligned with each beam path, and means mounting one of said tubular members coaxially on each beam path with one end enclosing an aperture through said plate and with the other end of each of said tubular members adjacent said second electrode, said target electrode including a support plate having a plurality of groups of phosphor dots with one phosphor dot of each group having a different color of luminescence when bombarded with electrons, and a masking electrode closely spaced from said support plate between said support plate and said electron gun means for masking all except one of the phosphor dots of each of said groups from the electron beam of each gun.
